Inventor:

Charles A. Hoxie

by Alexander S. Grant.
His Attorney,

UNITED STATES PATENT OFFICE

CHARLES A. HOXIE, OF SCHENECTADY, NEW YORK, ASSIGNOR TO GENERAL ELECTRIC COMPANY, A CORPORATION OF NEW YORK

LOUD-SPEAKER

Application filed September 13, 1922. Serial No. 588,088.

My present invention relates to sound reproducing devices, and more particularly to devices capable of actuation by electric currents and adapted to reproduce faithfully 5 and in good volume sounds by means of which the actuating currents have been produced.

One disadvantage which has been present in most devices which have been used for the purpose set forth above has been the fact 10 that the necessary moving elements employed have possessed natural rates of vibration within the range of frequency of the sounds to be reproduced, and as a result sound having a frequency corresponding to this natural frequency have been accentuated more 15 than sounds of other frequencies, and distortion has resulted.

One of the objects of my invention is to overcome this disadvantage and provide a 20 device the moving elements of which have no natural rates of vibration within the range of the readily audible frequencies.

My improved device belongs to the general class in which the sound producing diaphragm is actuated by means of a movable element which in turn is directly actuated 25 by the electric currents applied to the device. If either the diaphragm or the actuating element therefor have natural rates of vibration 30 within the range of frequency of the sounds to be reproduced, the distortion mentioned above will be present. I prevent such distortion by constructing both the diaphragm and the actuating element therefor in such a 35 way that they will have no objectionable natural rates of vibration. The diaphragm actuating element which I employ is in the form of an elongated member supported at both ends and of such rigid construction that 40 any natural rate of vibration which it may have will be greater than the frequency of any of the sounds to be reproduced.

Another essential feature of such a device 45 is that the moving parts shall have small inertia. To reduce to a minimum the inertia of the moving parts, I make the actuating element of some comparatively light metal, such as aluminum. The usual form of diaphragm employed in devices of the type here under 50 consideration has consisted of a thin flexible

sheet of metal or other material, such as mica, rigidly secured at its periphery. Such diaphragms usually have at least one, and in some cases more than one, natural rate of vibration within the range of frequency of the sounds to be reproduced. I overcome this 55 disadvantage by employing a diaphragm of rigid construction and securing it in the device in such a way that the only movement of one part of the diaphragm with respect to another part takes place at or near the periphery. In other words, the greater portion of the diaphragm moves as a whole, and substantially all of the internal stresses 60 produced take place near the periphery. This result may be conveniently brought about by making the diaphragm in the form 65 of a cone having its base surrounded by a flat narrow ring by means of which it is secured in the device.

The novel features which I believe to be 70 characteristic of my invention are set forth with particularity in the appended claims. My invention itself, however, both as to its organization and method of operation will 75 best be understood by reference to the following description taken in connection with the accompanying drawing, in which Fig. 1 is a vertical cross-section of one of my devices; Fig. 2 is a perspective view with a 80 portion of the actuating mechanism removed, and Fig. 3 is a perspective view of the actuating coils and the mounting therefor.

As indicated in the drawing, a base 1 is 85 provided having attached thereto an upright support member 2. The actuating mechanism comprises a pair of permanent magnets 3 and 4, each of which has opposing poles 5, 5 separated by a short air gap. The magnets are held in proper spaced relation to 90 each other by a bridging member 6, to which they may be secured in any desired manner. The bridging member 6 is secured by means of screws 7 to the bracket 8 which is formed on the member 9. The upright supporting member 2 is provided with posts 10, 10 and 11, 11. The diaphragm actuating member 12 is secured to the posts 10, 10 by means of the screws 13, 13 as indicated. The actuating member 12 is in the present case made of a 95 100

tube of light metal, such as aluminum, supported at its ends by the posts 10, 10 and flattened at its middle portion. Before the tube is flattened a sleeve 14 of magnetic material is slipped on it and flattened with the tube to form an armature. The magnets 3 and 4 are so mounted that the armature 14 is located in the air gaps of the magnets. The magnets are secured to the supporting member 2 by means of screw-bolts 15 which pass through slots in the support 2 to permit of vertical adjustment of the magnets. Such vertical adjustment to accurately center the armature 14 in the air gaps of the magnets is provided by the adjusting screws 16 and 17 which pass through the posts 10 and 11.

The actuating coils 18 surround the armature 14 and are secured to a bracket 19 which is fastened to the support 2. The armature 14 is connected by a link 20 to the diaphragm 21. The diaphragm 21 is made of conical form to give it the desired rigidity without excessive weight. In the form illustrated, the base of the cone is secured to a ring 22 which may be of comparatively flexible material, such as mica, and the ring 22 is clamped between a ring 23, which is secured to the support 2, and a clamping ring 24 by means of the screws 25. A narrow sound chamber with an outlet 26 is formed by means of the cover 27. The tubular extension 28 of the cover 27 provides a means for securing to the device a horn of any desired form. The protective casing 29 encloses the actuating mechanism of the device.

A diaphragm actuating element such as described may be made so rigid that any natural vibration frequency which it possesses will be above the frequencies of the sounds to be reproduced, and hence no distortion of the sound will be produced by reason of this element. The conical portion of the diaphragm 21 will also move as a whole, substantially no relative movement between different portions being produced by the actuation of the diaphragm. Substantially all of the internal stresses produced in the diaphragm will be produced in the ring 22.

It will also be observed that the center of the diaphragm is located directly above the center of the actuating element, and that the connecting link 20 moves straight up and down, thus permitting the use of a rigid connection of the connecting link to both the diaphragm and the actuating element. By this construction none of the energy available is uselessly employed in bending the connecting link, and the connection is free from any lost motion such as is inherent in any link connection involving two or more members having relative movement with respect to one another.

The actuating element 12 may, if desired, be so constructed that a portion of the bending thereof will take place in the middle por-

tion which is located in the air gaps of the magnets 3 and 4. Preferably, however, the armature 14 is made thick enough to reinforce the middle portion to such an extent that substantially all of the bending will occur in the end portions of the actuating element between the armature 14 and the supports. As a result of such construction the armature moves as a whole across the air gaps with substantially the same relative movement between all parts thereof and the poles of the magnet and no relative movement between different parts thereof, and the attraction between the armature and the nearest magnet pole is substantially uniform throughout the entire area of the air gaps whenever the actuating element is deflected from its central position.

While I have shown and described the preferred embodiment of my invention, it will be apparent that my invention is by no means limited to the precise embodiment shown, but that many modifications therein may be made without departing from the scope of my invention as set forth in the appended claims.

What I claim as new and desire to secure by Letters Patent of the United States, is:—

1. A sound reproducing device comprising a diaphragm actuating element consisting of a tubular member rigidly supported at its ends and flattened at its middle portion.

2. A sound reproducing device comprising a diaphragm actuating element consisting of a tubular member of non-magnetic material supported at its ends and flattened at its middle portion, and a member of magnetic material secured to the middle portion thereof.

3. A sound reproducing device comprising a diaphragm actuating element consisting of a tubular member of non-magnetic material rigidly supported at its ends and flattened at its middle portion.

4. A sound reproducing device comprising a diaphragm actuating element consisting of a comparatively light elongated rigid member which is rigidly supported at its ends and is more flexible at its end portions than at its middle portion.

5. In a sound reproducing device a diaphragm actuating element comprising a comparatively light elongated rigid member of non-magnetic material which is supported at its ends and is more flexible at its end portions than at its middle portion.

6. A sound reproducing device comprising a diaphragm actuating element consisting of a comparatively light elongated rigid member of non-magnetic material which is supported at its ends and a member of magnetic material secured to its middle portion, said element being more flexible at its end portions than at its middle portion.

7. A sound reproducing device comprising a diaphragm actuating element consisting of

- an elongated member of non-magnetic material supported at its ends, a member of magnetic material secured to its middle portion, and a pair of magnets each of which has a pair of opposing poles separated by a short air gap, the middle portion of said element being supported in the air gaps of said magnets. 5
8. A sound reproducing device comprising a diaphragm actuating element consisting of an elongated member rigidly supported at its ends and a pair of magnets each of which has a pair of opposing poles separated by a short air gap, the middle portion of said element being supported in the air gaps of said magnets, and an actuating coil surrounding the middle portion of said element. 10
9. A sound reproducing device comprising a diaphragm actuating element consisting of an elongated member of non-magnetic material supported at its ends, a member of magnetic material secured to its middle portion, and a pair of magnets each of which has a pair of opposing poles separated by a short air gap, the middle portion of said actuating element being supported in the air gaps of said magnets, and an actuating coil surrounding the middle portion of said actuating element. 15
10. A sound reproducing device comprising a diaphragm actuating element consisting of a tubular member supported at its ends and flattened at its middle portion, and a pair of magnets each of which has a pair of opposing poles separated by a short air gap, the flattened middle portion of said element being supported in the air gap of said magnets. 20
11. A sound reproducing device comprising a diaphragm actuating element consisting of a tubular member of non-magnetic material supported at its ends and flattened at its middle portion, a member of magnetic material secured to its flattened middle portion, and a pair of magnets each of which has a pair of opposing poles separated by a short air gap, the flattened middle portion of said element being supported in the air gaps of said magnets. 25
12. A sound reproducing device comprising a diaphragm actuating element consisting of a tubular member of non-magnetic material supported at its ends and flattened at its middle portion, a member of magnetic material secured to its flattened middle portion, and a pair of magnets each of which has a pair of opposing poles separated by a short air gap, the flattened middle portion of said element being supported in the air gaps of said magnets, and an actuating coil surrounding the flattened middle portion of said element between said magnets. 30
13. A sound reproducing device comprising a diaphragm, a rigid diaphragm actuating element supported at its ends and having its middle portion located in a short air gap between opposing magnetic poles, and a rigid connection between the center of said element and the center of said diaphragm, the natural frequency of vibration of said element being greater than that of the sounds to be reproduced. 35
14. A sound reproducing device comprising a diaphragm, an elongated diaphragm actuating element supported at its ends and having its middle portion located in an air gap between opposing magnetic poles which is short in comparison with the width of said element, the center of said diaphragm being directly above the center of said actuating element, and a rigid connection between the center of said diaphragm and the center of said actuating element. 40
15. A sound reproducing device comprising a diaphragm, a diaphragm actuating element consisting of a tubular member supported at its ends and flattened at its middle portion, and a rigid connection between said diaphragm and said actuating element. 45
16. A sound reproducing device comprising a diaphragm, a diaphragm actuating element consisting of a tubular member of non-magnetic material supported at its ends and flattened at its middle portion, a member of magnetic material secured to the middle portion thereof, and a rigid connection between said diaphragm and said actuating element. 50
17. A sound reproducing device comprising a diaphragm, a diaphragm actuating element consisting of a tubular member of non-magnetic material supported at its ends and flattened at its middle portion, and a rigid connection between said diaphragm and said actuating element. 55
18. A sound reproducing device comprising a diaphragm, a diaphragm actuating element consisting of a comparatively rigid member which is supported at its ends and is more flexible at its end portions than at its middle portion, and a rigid connection between said diaphragm and said actuating element, the natural frequency of vibration of said element being greater than that of the sounds to be reproduced. 60
19. A sound reproducing device comprising a diaphragm, a magnet having a pair of opposing poles separated by a short air gap, a diaphragm actuating element consisting of a rigid elongated member supported at its ends and having its middle portion located in the air gap of said magnet, and a rigid connection between the center of said diaphragm and the center of said actuating element, the natural frequency of vibration of said element being greater than that of the sounds to be reproduced. 65
20. A sound reproducing device comprising a diaphragm, a diaphragm actuating element consisting of an elongated member supported at its ends, a pair of magnets each 70
- 75
- 80
- 85
- 90
- 95
- 100
- 105
- 110
- 115
- 120
- 125
- 130

of which has a pair of opposing poles separated by a short air gap, the middle portion of said element being supported in the air gaps of said magnets, an actuating coil surrounding the middle portion of said element, and a rigid connection between the center of said diaphragm and the center of said actuating element.

21. A sound reproducing device comprising a diaphragm, a diaphragm actuating element consisting of an elongated member supported at its ends, a pair of magnets each of which has a pair of opposing poles separated by a short air gap, the middle portion of said element being supported in the air gaps of said magnets, an actuating coil surrounding the middle portion of said element, and a straight connecting link rigidly secured to the center of said diaphragm and to the center of said actuating element.

22. A sound reproducing device comprising a diaphragm, a relatively rigid diaphragm actuating element supported at its ends, an actuating coil surrounding said element, and a rigid connection between the center of said element and the center of said diaphragm.

23. A sound reproducing device comprising a diaphragm, a relatively rigid diaphragm actuating element supported at its ends, the center of said diaphragm being located directly above the center of said actuating element, an actuating coil surrounding said element, and a rigid connection between the center of said element and the center of said diaphragm.

24. A sound reproducing device comprising a diaphragm, a rigid diaphragm actuating element supported at its ends, the center of said diaphragm being located directly above the center of said actuating element, an actuating coil surrounding said element, and a straight connecting link rigidly secured to the center of said diaphragm and to the center of said actuating element.

25. A sound reproducing device comprising a diaphragm actuating element consisting of a tubular member of non-magnetic material supported at its ends and flattened and reinforced at its middle portion by magnetic material so that the end portions are more flexible than the middle portion.

26. A sound reproducing device comprising a diaphragm actuating element consisting of an elongated member supported at its ends, said member being more flexible at its end portions than at its middle portion, and a pair of magnets each of which has a pair of opposing poles separated by a short air gap, the middle portion of said element being supported in the air gaps of said magnets, and an actuating coil surrounding the middle portion of said element.

27. A sound reproducing device comprising a diaphragm actuating element consist-

ing of a tubular member of non-magnetic material supported at its ends and flattened at its middle portion, a member of magnetic material secured to its flattened middle portion and reinforcing the middle portion to make the middle portion more rigid than the end portions, and a pair of magnets each of which has a pair of opposing poles separated by a short air gap, the flattened middle portion of said element being supported in the air gaps of said magnets.

28. A sound reproducing device comprising a diaphragm, a magnet having a pair of opposing poles separated by an air gap, a diaphragm actuating element comprising an armature located in the air gap of said magnet, said air gap being short in comparison with the width of said armature, said armature being so constructed and arranged that when actuated all parts thereof in the air gap will have substantially the same relative movement with respect to the magnet poles, and a rigid connection between the armature and the diaphragm.

29. A sound reproducing device comprising a magnet having a pair of opposing poles separated by an air gap and a diaphragm actuating element comprising a member of magnetic material located in the air gap of said magnet, said air gap being short in comparison with the width of said member, said member being so constructed and supported that when actuated all parts thereof in the air gap will have substantially the same relative movement with respect to the magnet poles.

30. A sound reproducing device comprising a conical diaphragm of light rigid material, a ring of more flexible material secured to the outer edge of said diaphragm, supporting means for said ring of flexible material, an elongated vibratory member provided with a resilient bendable support and located in a pair of short air gaps between opposing magnetic poles, an actuating coil surrounding the middle portion of said member and a connecting rod between said member and the central portion of said diaphragm.

31. A sound reproducing device comprising a conical diaphragm of light rigid material, a ring of more flexible material secured to the outer edge of said diaphragm, supporting means for said ring of flexible material, an elongated vibratory member provided with a resilient bendable support and located in a pair of short air gaps between opposing magnetic poles, means for vibrating said member, and a connecting rod between said member and the central portion of said diaphragm.

32. A sound reproducing device comprising a conical diaphragm of light rigid material, a ring of more flexible material secured to the outer edge of said diaphragm, sup-

- porting means for said ring of flexible material, a vibrating member provided with a resilient bendable support and of magnetic material located in a pair of short air gaps between opposing magnetic poles, an actuating coil surrounding the middle portion of said member and a connecting rod between said member and the central portion of said diaphragm.
33. A current responsive device comprising an actuating element consisting of an elongated member rigidly supported at its ends and a pair of magnets each of which has a pair of opposing poles separated by a short air gap, the middle portion of said element being supported in the air gaps of said magnets and an actuating coil surrounding the middle portion of said element.
34. A current responsive device comprising an actuating element consisting of a tubular member of non-magnetic material supported at its ends and flattened at its middle portion, a member of magnetic material secured to its flattened middle portion, and a pair of magnets each of which has a pair of opposing poles separated by a short air gap, the flattened middle portion of said element being supported in the air gaps of said magnet.
35. In witness whereof, I have hereunto set my hand this 12th day of September, 1922.

CHARLES A. HOXIE.
